UNITED STATES PATENT OFFICE.

LOUIS GICLAS, OF WASHINGTON, DISTRICT OF COLUMBIA.

SIGNALING MEANS FOR TOY BANKS AND FOR OTHER PURPOSES.

Application filed June 4, 1921. Serial No. 475,075.

To all whom it may concern:

Be it known that I, LOUIS GICLAS, citizen of the United States, residing at Washington, District of Columbia, have invented 5 certain new and useful Improvements in Signaling Means for Toy Banks and for Other Purposes, of which the following is a specification, reference being had therein to the accompanying drawing.

10 This invention relates primarily to improvements in signaling means capable of a variety of uses such as in connection with a toy banks, show windows, advertising devices, light houses, etc., all as will be more 15 apparent from the specific description hereinafter set forth.

In a preferred embodiment of the invention, my improved signaling means are employed in association with features operating 20 in combination to serve as a toy bank.

In keeping with the spirit of thrift, it is desirable that some inducements be offered to inspire the saving of small sums represented in coins, and it has been with this 25 thought in mind that I have conceived a bank which at certain times, as on the occasion of the insertion of a single coin, or after the accumulation of coins, or both, will set into action or motion a part of the mechanism which will represent or signal in some way that a coin has been deposited or that 30 a number of coins have been saved. To illustrate, I provide mechanism where, for example, on the introduction of a coin, the head of a figure will automatically nod in 35 recognition of approval; and on the accumulation of an amount of savings some other part or parts of the figure will act in the sense of a reward, to indicate that the goal 40 desired to be reached in the savings has been attained. In this way one is induced to save and will entertain the state of expectancy or desire to secure the automatic actuation of the device as the reward for the saving 45 and depositing from time to time of the amounts required to obtain that result.

In keeping with the foregoing conception, a convenient and practical form of mechanism embodying the invention comprises a 50 figure fashioned after Bartholdi's Statue of Liberty, the same having therewithin a receiver for coins operatively related to a coin slot or the like, combined with a movable head on the figure and connecting mech-

anism between the head and the coin slot 55 in part in the path of a coin to cause the coin to actuate the head in the course of insertion of the coin, said figure also having movable arms bearing illuminating devices or appropriate words, and mechanism between the 60 same and the coin receiver so that the latter, following the accumulation of coins therein, will move or otherwise exert a control to effect the actuation of said arms and also the illuminations associated therewith. Details in the construction and arrangement of parts of the device will now be described, but here it is to be understood that the construction and arrangement is capable of much modification without departing from 70 the spirit of the invention as incorporated in the hereto appended claims.

In the drawings:

Figure 1 is a perspective view of the bank; Figure 2 is a vertical sectional view of 75 the same;

Fig. 2^a is a diagram of the electric circuit;

Figure 3 is a detail side view;

Figure 4 is a transverse sectional view; and

Figures 5 and 6 are detail sectional views.

Referring more specifically to the drawings, wherein like reference letters designate like parts in the several views, A represents a casing formed of sheet metal of any desired 85 sections found expedient in assembling the same into the whole, same having the general contour of the Statue of Liberty with the enlarged base portion B, the head C, and the arms D and E, respectively. Within the 90 enlarged base is a coin tray F having its upper part open so that coins may fall thereinto when inserted through the coin slot represented at G. The coin tray or receiver F is adapted to have a freedom of 95 movement in a vertical direction and rests centrally upon the shorter end of a lever H fulcrumed at h in somewhat elevated position to the bottom of the device, the longer end of the lever bearing a weight h' which 100 is adapted to normally overcome the weight of the coin tray or receiver F and hold the same in elevated position until a sufficient quantity of coins has been deposited in the tray or receiver to overcome the weight h' 105 and permit the tray or receiver to depress the shorter end of the lever correspondingly elevating the longer end thereof with its

accompanying weight. All this is for a purpose as will presently appear.

The head C is pivoted to the main or body portion of the figure as at c so that the head 5 may be subjected to a nodding action, such action being desirably obtained coincidently with the insertion of a coin through the coin slot G. To this end an arrangement of pivoted levers J and j are provided, the former 10 connected to the head in advance of the pivot c and the latter having its free arm arranged in the path of the coin introduced through the coin slot G, said levers being connected by suitable linkage j'.

15 The end of the lever j projecting into the path of the coin will compel the coin to rock said lever and correspondingly transmit rocking or nodding movement to the head of the figure as will be obvious.

20 The left arm D of the figure is bent somewhat at the elbow as shown and normally assumes an approximately horizontal position, the hand carrying the representation of a book, as at d entitled for example, 25 "Law". This particular arm is pivoted in the region of the elbow as at K to convert the same into a lever, the shorter or actuating position k of which is intended to be engaged by additional means to cause an up 30 and down swinging movement of the arm as will soon appear.

The other or right arm E of the figure is extended and uplifted and carries a lamp or light e or some other equivalent device, the lamp formation preferably bearing the word 35 "Light".

This arm E is provided with a ball and socket connection L movably uniting the same with the main or body portion of the 40 figure and downwardly beyond said joint L, the arm has a rigid projecting or stem portion M arranged interiorly of the device and terminating approximately axially of the latter. The short arm k of the arm-like 45 lever D has an inwardly projecting lug k' extending through an aperture a in the body of the figure so that the free end of the lug is also located interiorly of the device whereby both arms may be actuated by a common 50 actuator now to be defined. N is a spring motor mounted in the enlarged or base portion B of the device above the coin receiver F, the spring being adapted to be secured at one end to the casing and at the other end 55 to a vertical shaft O. Suitable gearing n with a shaft n' leading to the exterior of the casing is furnished to enable winding of the motor through the medium of a suitable key, handle or the like. On the bottom 60 of the shaft O below the spring N is a ratchet n² with which a dog or pawl f engages to prevent unwinding of the spring, the weight h' operating through the coin tray to which said pawl or dog is fixedly secured serving to keep the latter in operative 65

engagement with the ratchet until the coins depress the tray, thus overcoming the weight and releasing the spring motor.

At the upper end of the vertical shaft O and fastened to rotate therewith is a cam block P, the upper portion of which is hollow as at p and bridged by a diaphragm or top wall p' having an eccentrically disposed slot m through which the extension M of the arm E works to secure a back and forth movement of the arm as the cam block P rotates with the spindle O when the spring motor N is released. Around the periphery of the cam block is a peripheral cam way k² into which the lug k' on the arm D projects so that as the cam block rotates the arm D will be given its up and down movement to which reference has been previously made.

From the foregoing it will be appreciated that the head of the device will nod as in approbation each time any coin is inserted into the device, and at some future time when the predetermined weight of coins has accumulated in the coin tray, the latter will automatically lower itself within the casing, release the motor, and the motor will thereupon instantly operate its shaft or spindle and through the cam block and connections swing both arms on their pivots to give the 95 desired animation to the figure as a reward for the effort and thrift in saving the amount necessary to secure such operation. In addition the device effectively brings to the mind of the child the words "Light" and 100 "Law", or such other words as will impress on the mind matters of a wholesome character.

At times the effect of the device will be enhanced by illumination and to that end the element representing the law book d and the lamp e may in fact be lamps such as transparent casings, or perforated casings with electric bulbs X and in electric communication with such bulbs, I provide wiring leading from a battery Q having a switch R the terminals of which are normally spaced or broken, but which are adapted to be closed by the lowering movement of the filled coin tray so that simultaneously with the movement of the arms D and E the same will be illuminated. Associated with the same battery Q I arrange wiring leading to a bulb within the head, the broken switch in this instance represented at S being at the coin slot so as to be closed through the coin as the coin is passing through the slot, thus effecting illumination of the head when desired, the metal of the head being perforated 115 for that purpose.

The friction between the various movable parts will be sufficient to exert a retarding influence against overspeeding of the spring motor and will obviate the necessity of a 130

balance wheel although it is clear that one may be provided if found necessary in any special instance, or any usual escapement furnished.

5 The head C of the figure is pivoted toward the rear of the head so that the forward weight thereof will normally seat the head and maintain the levers J and j and connecting linkage j' in operative position by 70
10 restoring themselves after a coin in its passage through the coin slot into coin chute g has momentarily shifted or nodded the head.

It will be seen that whereas one particular embodiment of the invention, namely: 15 the bank, has been disclosed in this application, such disclosure is for the purpose of imparting a complete understanding of the invention only because as mentioned at the 20 outset of this specification, the device is capable of other uses. The Statue of Liberty always appeals to the public and the use of the motor actuated figure in a window (devoid of the bank feature) will be attractive 25 and valuable as an advertising medium. Again, in actual river or harbor uses, it is felt that the device will find a serviceable field because of its particular nature from 30 ornamental and patriotic aspects during the day supplemented by the movable nature of signaling lights during the night.

In lieu of the constant illumination effected through the battery Q and connections, intermittent illumination may be obtained by providing a depending pin or pins 35 T on the bottom of the cam block P adapted in its rotation to alternately close automatically opened spring switch terminals U and V, respectively in circuit with the lamp 40 or torch e and member d on the arm D to flash the same at intervals.

Having thus described the invention, what I claim is:

1. A bank of the character described comprising a coin receiver, movable illuminating signaling means, means for illuminating said signaling means, means operatively associated with said movable illuminating signaling means and coin receiver rendered effective upon an accumulation of coins in the coin receiver for actuating the movable signaling means, and means connected with the signaling means and actuated by the coin receiver for setting in action the illuminating means.

2. A bank of the character described comprising a casing in the shape of a figure, an arm mounted for oscillation on the figure, an arm extended outwardly and mounted for axial rotation, a coin receiver mounted for vertical movement in the casing and adapted to be depressed by a predetermined number of coins deposited in said receiver, a motor, means operatively connecting the motor with the arms for causing movements

of the arms, means for maintaining the motor against operation and connected with the receiver, said means adapted to be maintained for releasing the motor when the coin receiver has been depressed.

3. A bank of the character described comprising a casing in the shape of a figure, an arm mounted for oscillation on the figure, an arm extended outwardly and mounted for axial rotation, a coin receiver mounted for vertical movement in the casing and adapted to be depressed by a predetermined number of coins deposited in said receiver, a motor, means operatively connecting the motor with the arms for causing movement of the arms, means for maintaining the motor against operation and connected with the receiver, said means adapted to be maintained for releasing the motor when the coin receiver has been depressed, 75
80
85
90
95
100
105
110
115
120
125
130

4. A bank of the character described comprising a casing in the shape of a figure, a coin receiver mounted for movement in the casing and adapted to be depressed by a predetermined number of coins deposited in said receiver, said casing being provided with movable arms, a motor operatively connected with said arms, means between the coin receiver and the motor controlling actuation of the motor, said last mentioned means releasing the motor for operation upon accumulation of a predetermined number of coins in the receiver.

5. A bank of the character described comprising a casing in the shape of a figure, a coin receiver mounted for movement in said casing and adapted to be depressed by a predetermined number of coins deposited in said receiver, a slotted member for directing coins to the receiver, means for maintaining the receiver against movement until a predetermined number of coins have been deposited in said receiver, a motor, means connecting the motor with the receiver for maintaining the motor against movement during the inactive position of the receiver, arms movably mounted on the casing and operatively connected with the motor, said motor causing actuation of the arms when the receiver has released said motor.

6. In a bank of the character described, a casing in the nature of a figure, provided with a door locked against unauthorized manipulation, a coin receiver in said casing, a slotted member for the introduction and for directing coins to the receiver, said casing being provided with arms, one of the arms mounted for oscillation at one side of a figure, the other arm extending upwardly from said figure and mounted for rotation, a cam mem-

ber for oscillating the first mentioned arm and rotating the second arm, a motor mounted within the casing and operatively connected with the cam member, a retaining 5 means on the coin receiver for maintaining the motor against operation, said coin receiver being moved upon the accumulation of a predetermined number of coins in the same for displacing the retaining means to 10 release the motor whereby the arms are operated.

7. A device of the character described comprising a casing in the nature of a figure, the same having movable arms, a motor, a 15 member adapted to be rotated by the motor, said member having an eccentric at one end and a peripheral cam way, and connections between one of the arms and said eccentric to move the arm in upraised position and 20 between the other arm and the cam way to move the arm to forwardly extended position.

8. A device of the character described comprising a casing in the nature of a figure, 25 the same having a movable arm carrying signaling means, and a motor for actuating said arm, in combination with means for periodically illuminating said signaling means.

30 9. A device of the character described

comprising a casing in the nature of a figure having movable arms, signaling means associated with each of said arms, and means for actuating said arms to effect movement thereof with the signaling means carried thereby, means for effecting periodic illumination of said signaling means, means for maintaining the actuating means against operation, said means being releasable upon a predetermined number of coins being inserted into the casing. 40

10. A device of the character described comprising a casing in the nature of a figure having movable arms, and means for actuating said arms to effect movement thereof with the signaling means carried thereby, 45 means for effecting periodic illumination of said signaling means and alternately with respect to said arms means for maintaining the actuating means against operation, said means being releasable upon a predetermined number of coins being inserted into the casing. 50

In testimony whereof I hereunto affix my signature in the presence of two witnesses.

LOUIS GICLAS.
